Primary Examiner — Cynthia R Underwood

(74) *Attorney, Agent, or Firm* — Heedong Chae; Lucem, PC

CLAIM

The ornamental design for a case for electronic communications device, as shown and described.

DESCRIPTION

FIG. 1 is a front perspective view of a case for electronic communications device showing my new design;
FIG. 2 is a rear perspective view thereof;
FIG. 3 is a front elevational view thereof;
FIG. 4 is a rear elevational view thereof;
FIG. 5 is a left side elevational view thereof;
FIG. 6 is a right side elevational view thereof;
FIG. 7 is a top plan view thereof;
FIG. 8 is a bottom plan view thereof;
FIG. 9 is rear perspective view thereof, shown in an environment of use; and,
FIG. 10 is an exploded rear perspective view of the case. The broken lines depict environmental subject matter and portions of the case for electronic communications device that form no part of the claimed design.

1 Claim, 10 Drawing Sheets
